UNITED STATES PATENT OFFICE.

GRANVILLE R. LEWIS, OF LYNCHBURG, VIRGINIA.

CAR-COUPING.

SPECIFICATION forming part of Letters Patent No. 439,410, dated October 28, 1890.

Application filed July 11, 1890. Serial No. 358,433. (No model.)

To all whom it may concern:

Be it known that I, GRANVILLE R. LEWIS, a citizen of the United States, residing at Lynchburg, in the county of Campbell and State of Virginia, have invented certain new and useful Improvements in Car-Couplings; and I do hereby declare the following to be a full, clear, and exact description of the invention, such as will enable others skilled in the art to which it appertains to make and use the same.

This invention relates to improvements in car-couplings, which will be hereinafter more particularly described and pointed out.

In the accompanying drawings, forming part of this specification, Figure 1 is a side view of the coupling. Fig. 2 is an end view of Fig. 1. Fig. 3 is a plan view of a coupling-link.

A is the end sill of a car, and B B the buffers.

B' is a hinge by which the coupling-pin is pivoted.

a is the coupling-pin, which has a hinge B', with its pivot some distance beyond the pin outside, so that the pin by its weight will quickly fall to the vertical position shown in Fig. 1.

b is the bolt or pivot of the hinge B'.

c is a bent lever pivoted by a bolt d.

e is a chain attaching the lever c to levers f d' f d' on the end sill A. The chain e is extended upwardly to the top of a car.

f' f' are projections from the inside of the upper part of the coupler, forming inclined surfaces to guide the link to its place.

h is a rod at the upper end of the chain e.

h' is a groove in the coupler for the link to rest in.

i is a sectional view of the end of the link.

j is the lower lip of the coupler.

k is a curved broken line showing the path of the bottom of the coupling-pin when it moves inwardly.

k' is a key for fastening the bolt d.

m is the draw-head.

C is a link having an open hook i' at each end and the reversed curve l l' interiorly and an opening l'' of proper length to give sufficient play for the pin, and to prevent it from being lifted out of the slot when the cars are being backed. The middle part of the link is solid to give strength to the link. The curved recess x on one side allows more lateral play on that side.

The operation of this coupling is as follows: The link C is placed in a horizontal or inclined position, as may be required to couple the cars, in the draw-head of one car, resting in the groove h'. When the cars come together, the outer end i' of the link will shove the coupling-pin inwardly ahead of it, and the lower end of the pin will swing on the curved line k until the end i' of the link passes entirely under it, when the pin by its own gravity will drop back into the space l''.

To uncouple the cars, the brakeman from either side can move a lever d' f, or, being on top of the car, by means of rod h, can operate the bent lever c by lifting up the inner end c'', when the outer end c''' will move the outer end of the coupling-pin a and swing the lower end of it high enough on the curved line k to clear the link and release it from the pin.

I claim—

1. In a car-coupling, the link C, having at each end an open hook i', the slot l'', with the semicircular recess l', and reversed curve l, substantially as set forth.

2. In a car-coupling, the combination of the pivoted coupling-pin with the pivoted angular lever, one end of which swings the pin forward and the other end is connected with means for operating it from the top and sides of the car, as and for the purpose described.

In testimony whereof I affix my signature in presence of two witnesses.

GRANVILLE R. LEWIS.
